CLAIM

The ornamental design for a combined wireless keyboard and case for a portable electronic device, as shown and described.

DESCRIPTION

FIG. 1 is a front perspective view of a wireless keyboard and case for a portable electronic device showing our new design, shown in an open position for use;

FIG. 2 is a back perspective view thereof;

FIG. 3 is a front view thereof;

FIG. 4 is a back view thereof;

FIG. 5 is a side view thereof;

FIG. 6 is another side view thereof;

FIG. 7 is a top view thereof;

FIG. 8 is a bottom view thereof;

FIG. 9 is a front perspective view of the article shown in FIG. 1, shown in a closed position for use;

FIG. 10 is a back perspective view thereof;

FIG. 11 is a front view thereof;

FIG. 12 is a back view thereof;

FIG. 13 is a side view thereof;

FIG. 14 is another side view thereof;

FIG. 15 is a top view thereof; and,

FIG. 16 is a bottom view thereof.

(Continued)

The broken lines in the drawings depict parts of the combined wireless keyboard and case for a portable electronic device that form no part of the claim.
